HIGH VACUUM DISTILLATION APPARATUS

Kenneth C. D. Hickman, Rochester, N. Y., assignor to Distillation Products, Inc., Rochester, N. Y., a corporation of Delaware

Application August 3, 1944, Serial No. 547,891

6 Claims. (Cl. 202—205)

This invention relates to improved high vacuum distillation apparatus, and particularly to such apparatus wherein the vaporizing surface rotates and causes the distilland to flow thereover in a thin film by centrifugal force.

In all high vacuum, unobstructed path distillation apparatus heretofore used, the distilland was necessarily heated by conduction through a metal support for the film of distilland. The distilland was, therefore, initially heated from the under side of the film and distillation could not take place until this heat had passed through the film to its upper or free surface. In prior art apparatus of this type, the vaporizing and condensing surfaces were positioned opposite each other and since the vaporizing surface was at high temperature and the condensing surface at low temperature, considerable heat loss took place. The destruction that a labile substance undergoes in such a still is a composite of the elements of destruction which occurs in each successive layer of distilland from the hot support to the outside evaporating surface. Since this surface is facing a cold condenser, there must be a very high thermal gradient through the oil and destruction in the back layers may be abnormally high.

This invention has for its object to provide high vacuum, unobstructed path distillation apparatus whereby the foregoing difficulties are largely avoided. Another object is to provide high vacuum, unobstructed path distillation apparatus wherein the distilland film is, to a large extent, heated by application of heat to the distilling or free surface of the film. A further object is to provide high vacuum, unobstructed path distillation apparatus wherein the heat loss between the vaporizing and condensing surfaces is substantially lessened. A still further object is to improve the state of the art. Other objects will appear hereinafter.

These and other objects are accomplished by my invention which includes a high vacuum, unobstructed path distillation apparatus having a rotatable, spiral-shaped, vaporizing surface over which distilland is caused to flow in a thin film by centrifugal force and condensing surfaces positioned on each side of the spiral vaporizing surface whereby vapors can readily pass to the condensing surface but heat is radiated from one convolution of the spiral to the other instead of being lost by radiation to the condensing surface as heretofore.

In the following description I have set forth several of the preferred embodiments of my in-

vention, but it is to be understood that these are given by way of illustration and not in limitation thereof.

In the accompanying drawing wherein like numbers refer to like parts, I have illustrated two preferred forms of my invention wherein like numbers refer to like parts and wherein:

Fig. 1 is a vertical section of centrifugal still having a spiral-shaped vaporizing surface which is electrically heated and which is positioned between two rotatable condensing surfaces.

Fig. 2 is a vertical section of a modification of the apparatus illustrated in Fig. 1, being provided with a vaporizing surface having a double wall and with stationary perforated condensing surfaces, and

Fig. 3 is a fragmentary enlargement of the upper portion of the shaft bearing illustrated in Fig. 1.

Referring to Fig. 1, numeral 10 designates a cylindrical still casing provided with an integral base 13 and a removable cover 14 which forms a gas-tight joint with casing 10 at flange 16. Numeral 18 designates a hollow shaft which is closed at its lower end as indicated by dotted line 20 and which is housed in a rotatable manner in bearings 22 and 24.

Numeral 26 designates a spiral-shaped, vaporizing surface the inner portion of which is rigidly mounted upon shaft 18 and which is rigidly maintained in the position illustrated by supporting spiders 28 which are constructed of suitable insulating material. Spiral 26 is preferably of thin gauge metal so that it can be heated by its electrical resistance without undue waste of electricity. Spiral 26 is provided with inwardly turned edges 30 and with an inwardly turned end portion 32. The end of the spiral is also provided with a conduit 34 which protrudes into stationary gutter 36 which is connected to withdrawal conduit 38.

Referring especially to Fig. 3, numeral 40 designates a metal ring or commutator mounted upon shaft 18 but insulated therefrom by insulating material 42. Numeral 44 designates a bolt which is similarly insulated from shaft 18 and which is connected to electrical conductor 46 or commutator 40. Numeral 48 designates a brush making electrical contact with insulated commutator 40 and which is connected to a suitable source of electric current by conductor 50. Conductor 46 passes through a suitable insulating and gas-tight bushing 47 in the lower part of the wall of conduit 18 and is then connected to the outer end of spiral 26 in the manner illustrated. Numeral

52 designates a conductor which is grounded to the equipment and which leads to a suitable source of current in the same manner as conductor 50.

Numerals 54 indicates an annular channel in packed gland 24 to which is connected conduits 56 and 58. The lower portion of conduit 58 is connected to a number of perforations 60 in the wall of shaft 18 which serve to introduce distilland onto the inner portion of spiral vaporizing surface 26.

Numerals 62 and 64 designate circular condensing surfaces which are mounted upon shaft 18 and which rotate therewith. Numerals 66 and 68 designate circular gutters into which the peripheries of condensing surfaces 62 and 64 respectively protrude. Gutters 66 and 68 are connected to a withdrawal conduit 78 which is in turn connected to a cooler 72 and a conduit 74 through which distillate is withdrawn. Cooler 72 is connected to the intake side of circulating pump 76, the exhaust side of which is connected to filter 78. Numeral 80 designates a conduit for circulating cool, filtered distillate back onto the upper surfaces of condensing surfaces 62 and 64. Numeral 82 designates evacuating conduits connected to vacuum pumps (not shown).

Referring to Fig. 2 it will be noted that spiral-shaped, vaporizing surface 27 which is analogous to element 26 of Fig. 1 is double walled to permit heating by circulation of a heating fluid through the space between the double walls. Numerals 90, 92, and 94 designate annular channels in packed gland 24 to which are respectively connected conduits 96, 98, and 100. Numeral 102 designates a conduit connected at its upper end to an opening in shaft 18 at a point opposite channel 90 and which is connected at its lower extremity to the space between the double walls of vaporizing surface 27. Numeral 104 designates a conduit which similarly communicates at its upper extremity to channel 92 and which passes through the lower portion of the hollow shaft 18 and is connected at its lower extremity to the outer periphery of the space between the double walls of the spiral vaporizing surface. Numeral 106 designates a conduit communicating with channel 94 and with the inner inside surface of the spiral vaporizing surface by way of openings 60.

Numerals 108 and 110 designate condensers constructed in the form of a plurality of nested truncated cones which are spaced to permit the passage of non-condensable gases as described in Hickman and Hecker Patent 2,180,052, November 14, 1939. These condensers are provided respectively with gutters 112 and 114, at their lower portions into which condensate drains and is withdrawn respectively into conduits 116 and 118.

In operating the apparatus illustrated in Figs. 1 and 3 the system is evacuated through conduits 82. Shaft 18 is caused to rotate vaporizing surface 26 and condensing surfaces 62 and 64 as an integral unit. Electricity is applied to conductors 50 and 52 to heat vaporizing surface 26 to distillation temperature. Distilland is introduced through conduit 56, channel 54, thence through conduit 58 and opening 60 onto the inside of spiral-shaped, vaporizing surface 26. This distilland then flows by centrifugal force in a thin film over the inside surface of spiral 26. During this passage over 26, the distilland is heated to distillation temperature. Vapors are generated and pass sideways to condensing surfaces 62 and 64. Undistilled residue is prevented from being thrown by centrifugal force from the spiral 26 by end plate 32, and the residue, therefore, flows through conduit 34

and is thrown into gutter 36. This residue is then withdrawn from the still through conduit 38.

Condensate from condensing surfaces 62 and 64 is thrown into gutters 66 and 68 and flows thence into conduit 70. This condensate is partially bled off through conduit 74 and the remainder is cooled in cooler 72, is forced through filter 78 by pump 76 to remove material insoluble at the lower temperature, such as sterols. The cool, filtered condensate is then introduced by conduit 80 into the central recessed portion of condensing surfaces 62 and 64 and is then thrown by centrifugal force to the periphery thereof. This cool condensate serves to cool the condensing surfaces to a satisfactory, low, condensing temperature.

In operating the apparatus illustrated in Fig. 2, the system is evacuated as described above in connection with Fig. 1 and the spiral vaporizing surface 27 is rotated by force applied to shaft 18. Hot heating fluid is introduced through conduit 96 into channel 90 from which it flows through conduit 102 into the space between the double walls of spiral 27. Spent heating fluid passes into conduit 104 thence into channel 92 and flows from the still through conduit 98. Distilland is introduced through conduit 100 into channel 94 from which it flows through conduit 106 onto the inside part of spiral 27 by way of openings 60. Undistilled residue is caught in gutter 36 and is removed through conduit 38 as previously described. Condensate is condensed on condensers 108 and 110 which are cooled by conduits 116 and 118 respectively. The condensate flows into gutters 112 and 114 respectively and removed from the still by conduits 116 and 118 respectively. It will be noted that the condensing surfaces are segregated into individual portions spaced at different distances from the center of the spiral 27. Separate fractions will, therefore, be condensed on these separate portions and can be separately removed in the individual removal conduits as illustrated. While it makes little difference in which direction the spiral is rotated, it is preferred that the equipment as illustrated be rotated in a clockwise direction.

It is to be understood that many modifications can be made in the equipment illustrated without departing from the spirit or scope of my invention. Thus, the spiral convolutions may be widely or closely spaced. It is preferred for high vacuum, unobstructed path distillation that the convolutions be widely spaced. Also, the spiral may be a single lead spiral or multi-lead. The number of convolutions can, of course, be increased or decreased. The manner of circulating heating fluid shown in Fig. 2 can be modified considerably. Thus, the heating fluid may be a combined heating and heat exchange fluid as described in my co-pending patent application Serial No. 541,253, filed June 20, 1944. Other modifications will be obvious to those skilled in the art.

The invention has the outstanding advantage that heat loss between the vaporizing and condensing surfaces of a high-vacuum, unobstructed path still is greatly reduced. Another important advantage is that the distilland is not only heated by the supporting metal surface as heretofore, but is also heated by radiation from the inner convolutions so that the application of heat to the distilland is very efficient. Also, by partly obstructing the exit of vapor by placing a hot object near, although we raise the temperature of the surface by an amount necessary to compensate for the molecules returned, we may so

lower the thermal gradient that the fall in temperature and thus decomposition in the back layers of oil more than compensates for the rise of the front layers. The long spiral also gives the opportunity of much renewal of the distilling surface of turbulence.

What I claim is:

1. High-vacuum, unobstructed path distillation apparatus adapted to cause distilland to flow in a thin film by centrifugal force over a heated vaporizing surface, said apparatus comprising in combination a spiral-shaped, rotatable, vaporizing surface positioned between two condensing surfaces, and within a closed casing, means for maintaining a vacuum between the spiral-shaped, vaporizing surface and the condensing surfaces, means for introducing distilland onto the surface of the spiral vaporizing surface at a point near its center, means for removing undistilled residue from the outer portion of the spiral vaporizing surface, means for heating the spiral vaporizing surface, means for cooling the condensing surfaces, and means for removing the condensate from said condensing surfaces.

2. High-vacuum, unobstructed path distillation apparatus adapted to cause distilland to flow in a thin film by centrifugal force over a heated vaporizing surface, said apparatus comprising in combination a spiral-shaped, rotatable, vaporizing surface having a wide space between the convolutions of the spiral, which spiral is positioned between two condensing surfaces, and within a closed casing, means for maintaining a vacuum between the spiral-shaped vaporizing surface and the condensing surfaces, means for introducing distilland onto the surface of the spiral vaporizing surface at a point near its center, means for removing undistilled residue from the outer portion of the spiral vaporizing surface, means for heating the spiral vaporizing surface, means for cooling the condensing surfaces, and means for removing the condensate from said condensing surface.

3. High-vacuum, unobstructed path distillation apparatus adapted to cause distilland to flow in a thin film by centrifugal force over a heated vaporizing surface, said apparatus comprising in combination a spiral-shaped, rotatable, vaporizing surface, having a wide space between the convolutions of the spiral, which spiral is positioned between two rotatable condensing surfaces, and within a closed casing, means for maintaining a vacuum between the spiral-shaped vaporizing surface and the condensing surfaces, means for introducing distilland onto the surface of the spiral vaporizing surface, means for heating the spiral vaporizing surface, means for returning cooled condensate to the condensing surfaces, and means for removing the condensate from said condensing surfaces.

4. High-vacuum, unobstructed path distillation apparatus adapted to cause distilland to flow in a thin film by centrifugal force over a heated vaporizing surface, said apparatus comprising in combination a spiral-shaped, double walled, rotatable vaporizing surface, having a wide space between the convolutions of the spiral, which is positioned between two condensing surfaces, and within a closed casing, means for maintaining a vacuum between the spiral-shaped vaporizing surface and the condensing surfaces, means for introducing distilland onto the surface of the spiral vaporizing surface at a point near its center, means for removing undistilled residue from the outer portion of the spiral vaporizing surface, means for circulating heating fluid between the double walls of the spiral vaporizing surface, means for cooling the condensing surfaces, and means for removing the condensate from said condensing surfaces.

5. High-vacuum, unobstructed path distillation apparatus adapted to cause distilland to flow in a thin film by centrifugal force over a heated vaporizing surface, said apparatus comprising in combination a spiral-shaped, rotatable, vaporizing surface, having a wide space between the convolutions of the spiral which is positioned between two perforated condensing surfaces, and within a closed casing, means for maintaining a vacuum between the spiral-shaped, vaporizing surface and the perforated condensing surfaces, means for introducing distilland onto the surface of the spiral vaporizing surface at a point near its center, means for removing undistilled residue from the outer portion of the spiral vaporizing surface, means for heating the spiral vaporizing surface, means for cooling the condensing surfaces, and means for removing the condensate from said condensing surfaces.

6. High-vacuum, unobstructed path distillation apparatus adapted to cause distilland to flow in a thin film by centrifugal force over a heated, vaporizing surface, said apparatus comprising in combination a plurality of spiral-shaped rotating vaporizing surfaces having a wide space between the convolutions of each spiral which are mounted upon a single rotatable shaft, and each of which is positioned between two condensing surfaces, and within a closed casing, means for maintaining the vacuum between the spiral-shaped, vaporizing surfaces and the condensing surfaces, means for introducing distilland onto each of the spiral surfaces near the center thereof, means for removing undistilled residue from the outer portion of the spiral surfaces, means for heating the spiral surfaces, means for cooling the condensing surfaces, and means for removing condensate from said condensing surfaces.

KENNETH C. D. HICKMAN.
